DESIGN FOR A PROTECTIVE COVERING FOR A VACUUM CLEANER CASING OR THE LIKE

Malcolm S. Park, Mount Kisco, N. Y., assignor
to The Singer Manufacturing Company, Eliza-
beth, N. J., a corporation of New Jersey

Application August 17, 1938, Serial No. 79,409

Term of patent 7 years

To all whom it may concern:

Be it known that I, Malcolm S. Park, a citizen
of the United States, residing at Mount Kisco,
New York, have invented a new, original, and
ornamental Design for a Protective Covering for
a Vacuum Cleaner Casing or the like, of which
the following is a specification, reference being
had to the accompanying drawing, forming a
part thereof.

Fig. 1 is a perspective view of a protective cover-

ing for a vacuum cleaner casing or the like showing
my new design. Fig. 2 is a plan view of the
same.

The essential features of the invention reside
in the portions shown in full lines.

I claim:

The ornamental design for a protective cover-
ing for a vacuum cleaner casing or the like, as
shown and described.
